Patented Jan. 27, 1925.

UNITED STATES PATENT OFFICE.

JOHN H. COOK, OF SALT LAKE CITY, UTAH.

Application filed June 20, 1923. Serial No. 646,622.

To all whom it may concern:

Be it known that I, JOHN H. COOK, a citizen of the United States, residing at Salt Lake City, in the county of Salt Lake and State of Utah, have invented certain new and useful Improvements in Beds, of which the following is a specification.

The present invention relates to beds, particularly of the knockdown or collapsible type, the object being to provide a structure of a simple character that can be quickly set up and will provide a comfortable support or bottom.

In the accompanying drawings:

Figure 1 is a plan view of the bed, with a portion of the fabric broken away,

Figure 2 is a longitudinal sectional view on the line 2—2 of Figure 1,

Figure 3 is a detail sectional view on an enlarged scale, and taken on the line 3—3 of Figure 2,

Figure 4 is a side elevation of one of the corner portions of the frame;

Figure 5 is a detail sectional view illustrating the journal mounting of one of the rollers.

In the embodiment disclosed, an elongated angular frame is provided. This frame consists of corner heads 6, into which the ends of side rails or rods 7 are threaded. The heads at each end are also connected by transverse bars, preferably consisting of sections 8 that are threaded into the inner sides of the heads 6, and are connected by couplings 9. Legs 10 are threaded into the under side of the corner heads and support the frame at a suitable distance from the floor. The side rails 7, end pieces 8 and legs 9 may be made of stock tubing, and it will be evident that by detaching the parts the frame can be collapsed and packed into a relatively small space.

The corner heads 6 are provided on their inner sides with inwardly extending pintles 11, and journaled on said pintles are upstanding arms 12 that extend below and above said heads. The side rails 7 have secured thereto brackets 13, to which are connected the inner ends of coiled springs 14, the outer ends of said coiled springs being connected to the lower ends of the arms 12 and thus serving to urge the upper ends of said arms outwardly. The arms 12 have their upper end portions preferably curved outwardly, and said ends are provided with semi-circular sockets 15 adapted

to receive the pintles 16 of rollers 17 that are interposed between the upper ends of the arms at each end of the frame. It will be noted by reference to Figure 3 that the rollers 17 are tubes and that the pintles 16 are fitted into the ends of said tubes and fastened by rivets 18 or other suitable devices. The ends of the tubes 17 abut against the inner sides of the arms and the pintles 16 are held in the recesses 15 by semicircular caps 19 secured to the ends of the arms. Said pintles 16 are provided on the outer sides of the arms with ratchet wheels 20, the teeth of which are engaged by pawls 21 pivoted on the arms 12. The outer ends 22 of the pintles are angular to engage in corresponding sockets of a handle crank or wrench. Extending between the rollers 17 and spaced above the frame is a flexible fabric bed bottom 23 preferably of canvas or similar material and having its ends secured to and adapted to wrap upon said rollers 17.

When set up the bed is as shown in Figures 1 and 2, the fabric bottom being stretched tightly by turning both rollers, each roller moreover having ratchet wheels 20 and pawls 21 at both ends, so that there will be no give or uneven strain that will cause one side to be looser than the other. In thus stretching the fabric obviously the upper ends of the opposite arms 12 tend to move toward each other, thereby placing strain upon the springs 14, and these springs allow the necessary resiliency. As already stated the bed can be taken apart, and it will be evident that this can be conveniently accomplished since the elements of the frame can be readily detached and the arms 12 removed from their pintles after the rollers 17 have been disengaged from their mountings. In this connection, it will be noted that the arms are held on the pintles by the rollers that abut against the inner sides of said arms.

From the foregoing, it is thought that the construction, operation and many advantages of the herein described invention will be apparent to those skilled in the art, without further description, and it will be understood that various changes in the size, shape, proportion and minor details of construction, may be resorted to without departing from the spirit or sacrificing any of the advantages of the invention.

Having thus fully described my inven-

- tion, what I claim as new, and desire to secure by Letters Patent, is:—
1. A bed comprising a frame, sets of swinging arms at both ends of the frame, springs acting on the arms, rollers journaled on the arms and located transversely at the ends of the frame, means carried by the rollers whereby they can be rotated on the arms, means engaging the rollers and arms for preventing the retrograde rotation of the rollers, and a fabric bottom having its ends attached to the rollers and adapted to be wrapped thereupon. 35
  2. A bed comprising a frame, an arm at each corner of the frame pivoted between its ends to the frame, springs connected to the frame and to the lower ends of said arms, rollers journaled on the upper ends of the arms above the pivots of said arms and located at both ends of the frame, means on the arms engaging the rollers for holding the rollers against rotation in one direction and permitting their rotation in the opposite direction, and a fabric bottom having 40 its ends secured respectively to the rollers and adapted to be wrapped thereupon. 45
  3. A bed comprising a frame having corner heads provided with pintles on their inner sides, arms pivoted between their ends on said pintles, coiled springs connected to the sides of the frame and to the lower ends of the arms, a roller interposed between the upper ends of the arms at each end of the frame and journaled on said arms, 50

means whereby the rollers can be rotated in one direction and locked against retrograde rotation, and a fabric bed bottom extending between the rollers and having its ends secured thereto. 55

4. A bed comprising a frame having corner heads, frame bars and legs detachably engaged with said corner heads, upstanding arms pivotally and detachably mounted between their ends on the corner heads, springs connected to the lower ends of the arms and to the side bars of the frame, rollers having gudgeons journaled on the upper ends of the arms and having crank receiving ends and ratchet wheels, pawls on the arms engaged with the ratchet wheels, and a flexible fabric bottom having its ends secured to the rollers. 60

5. A bed comprising a frame, arms pivoted to the frame at one end, springs engaged with the arms to swing their upper ends outwardly, a roller journaled on the upper ends of the arms above their pivots, means for normally holding the roller against rotation but permitting it to be turned on the arms, and a fabric bed bottom having one end fastened to the roller and adapted to wrap thereupon. 65

In testimony whereof I affix my signature in the presence of two witnesses.

J. H. COOK.
